UNITED STATES PATENT OFFICE.

SYDNEY BURT GARDNER, OF BENSON, MINNESOTA.

TRENCH-WALL-SUPPORTING MACHINE.

1,391,624.

Specification of Letters Patent. Patented Sept. 20, 1921.

Application filed June 14, 1920. Serial No. 389,042.

To all whom it may concern:

Be it known that I, SYDNEY BURT GARDNER, a citizen of the United States, residing at Benson, in the county of Swift, State of Minnesota, have invented certain new and useful Improvements in Trench-Wall-Supporting Machines; and I do hereby declare the following to be a full, clear, and exact description of the invention, such as will enable others skilled in the art to which it applies to make and use the same.

The present invention relates to machines or devices for supporting the walls of trenches, such as required in sewer and drainage construction and in various other lines of work where it is required that the workmen operate in relatively narrow excavations.

An object of this invention is to provide a machine of this type which will take the place of the ordinary jack screws, braces, and other devices now commonly used for supporting the walls of the trenches against caving in, and which may be quickly and easily operated for supporting sheet piling or the like against the opposite walls of the trench for supporting those walls, particularly where the earth is of a sandy or other non-adhesive quality usually difficult to maintain from falling.

The invention has for another object to provide a machine which may be stepped lengthwise of the trench and also in a vertical direction so that it may be made to follow the line of work, and it may be quickly and easily operated for feeding the machine, either horizontally or vertically, for supporting piling or the like against the opposite walls of the trench at such points where it is required the work be carried on.

A further object of the invention is to provide a machine which may be operated by use of a relatively small amount of piling and which, when progressed in one direction, will release the rearmost piling and permit the positioning of the same in the front of the machine to thus use the same small amount of piling in the consecutive feeding or advancement of the machine.

The invention also has various other objects and advantages which will be in part understood from and in part specifically brought out in the following specification and illustrated in the accompanying drawings, in which:

Figure 1 is an end elevation of a trench

wall supporting machine constructed according to this invention and as arranged in a trench, the latter shown in cross section, and against piling for supporting the sides 60 of the trench.

Fig. 2 is a similar view showing the machine adjusted in position for advancement either vertically or horizontally in the 65 trench.

Fig. 3 is a side elevation of the machine showing one section thereof advanced horizontally.

Fig. 4 is a similar view showing the sections of the machine brought together in 70 position either before or after advancement in a horizontal direction.

Fig. 5 is an end view of the machine in the position shown in Fig. 4.

Fig. 6 is a horizontal section taken on the 75 line 6—6 of Fig. 5, and showing the sections in collapsed position.

Fig. 7 is a top plan view of the machine in the same position.

Fig. 8 is a detail enlarged sectional view 80 showing a slightly modified form of adjustable connection between one of the operating shafts and one of the advancing sections.

Fig. 9 is a transverse section taken through the same substantially on the line 9—9 of 85 Fig. 8; and

Fig. 10 is a detail perspective view showing a slight modification of one of the transverse bars for engagement with the wall of the trench.

Referring to the drawings, wherein like parts are designated by similar numerals of reference throughout the several views, 15 designates a trench or excavation in which a machine of this invention is adapted to be 95 used. The side walls of the trench 15 may be lined with piling 16 in the usual manner, and the piling is supported by the laterally extensible transverse members of the machine for holding the walls of the trench 100 from caving in or falling, or the sheet-piling may be omitted, and the sides of the walls of the trench will be supported by the arms 50 and 76, using improved section as shown by Fig. 10. That is the sheet-piling 105 need only be used when the material is of such nature that will require more bracing than the arms give.

The machine is composed in the main of a pair of relatively movable sections 17 and 110 18. Each section 17 and 18 is in the form of a frame having end members which are

joined, in each frame, by side pieces 19, and the latter may be constructed of angle iron for the purpose of lightness and rigidity. The end pieces of each frame comprise a pair of uprights 20 joined at their upper and lower portions by cross pieces 21 which rigidly hold the uprights in substantially parallelism and which brace and hold rigid each frame. The frames 17 and 18 are interfitting, or, as shown, the frame 18 has one end piece disposed between the end pieces of the frame 17 and is adapted to slide in the frame 17 within the limits of the operating mechanism, as will hereinafter appear. Means is provided for moving one of the frames or sections relatively to the other, the means being divided into a mechanism for relatively advancing the frames horizontally and another mechanism is provided for relatively advancing the frames in a vertical direction.

On the end of one of the sections, such as the section 18, is provided a bearing 22 in which is journaled a transversely extending crank shaft 23 having cranks 24 thereon which are disposed on opposite ends of the shaft 23 and extend in the same direction. These cranks 24 are connected by rods 25 to the adjacent end of the other section 17, so that upon rotation of the shaft 23 the sections 17 and 18 are moved relatively toward each other. The shaft 23 is provided intermediate its ends with a worm pinion 26 which meshes with a worm 27 on a shaft 28 projecting endwise from the frame 18 and journaled therein. The shaft 28 carries a sprocket wheel 29 over which is trained a sprocket chain 30 extending upwardly and over a second sprocket wheel 31 mounted on a drive shaft 32 which may be driven by power or otherwise, the hand crank 33 being disclosed for the purpose of illustration.

The said section 18 carries a gear housing or support 34 through which the drive shaft 32 extends, and the sprocket wheel 31 is loose on the drive shaft and is adapted to be coupled thereto when desired by a clutch element 35 shiftable on the shaft 32. The clutch 35 is shiftable by a hand lever 36 which preferably projects from the end of the gear casing 34 and within easy access of the operator.

The horizontal advancing means just described is set in operation by shifting the clutch 35 outwardly from the adjacent end of the section 18, and when the clutch element 35 is shifted inwardly it couples the drive shaft 32 with a sprocket wheel 37 normally loose on the drive shaft, and which engages a sprocket chain 38 which is carried upon an upper sprocket wheel 39 mounted on a stub shaft 40 carried upon the upper end of the section 18 and which projects longitudinally from the adjacent end 5 of the section.

The chain 38 also passes over a sprocket wheel 41 mounted on a shaft 42 which is journaled preferably at the side of the section 18, and which extends throughout substantially the entire length of the section. The other end of the shaft 42 is provided with a sprocket wheel 43 carrying a chain 44 which extends upwardly in the section 18 and passes over a sprocket wheel 45 mounted on a second stub shaft 46. The stub shafts 40 and 46 are arranged in pairs at opposite ends of the section 18 and are each provided with their respective sprocket wheels 39 and 45, the chains 38 and 44 passing over the pairs of sprocket wheels for causing the simultaneous turning of the stub shafts.

Each stub shaft is provided with a worm 47 which meshes with a worm pinion 48 fixed upon the upper end of an adjacent shaft 49, the shafts 49 extending vertically in pairs in each end of the section 18 and adapted to be simultaneously turned. The section 18 is provided on opposite sides and at suitably vertically spaced apart intervals with transverse bars 50 which may be of any desired construction, such as of channel iron construction, and which are supported near their opposite ends upon rods 51 slidably disposed through the uprights 20 of the section 18 for holding the bars 50 to the sections and permitting the movement of the bars toward and from the opposite sides of the section. The bars 50 being so mounted and forming a part of the other section 18 permit the expansion and contraction of the section 18 for a purpose which will later appear.

The bars 50 are adapted to be slid longitudinally by operation of the vertical shafts 49, and any suitable coupling means may be employed for transferring the rotation of the shafts 49 to a reciprocating movement of the rods 51. In the present instance the vertical shafts 49 are provided with crank portions 52 in line with the rods 51, and the rods are secured at their inner ends to the crank portions. The rods 51 are also provided with turnbuckles 53 or the like, permitting the expansion and contraction of the rods in the lengthwise direction for adjusting the presser bars 50 to trenches of varying widths.

In Figs. 8 and 9 of the drawing, the connection and adjustment of the rods is shown in a slightly modified form. In this instance the presser bars at the sides of the machine are provided with threaded spindles or rod portions 54 which engage in threaded relation in thimbles 55, and the latter have bearing for longitudinal sliding movement in a bracket 56 which is mounted upon the inner section, being the same as 20, thus forming a boxing or bearing for shaft 49. That is the bracket should be attached to the main frame, so as to make 130

a rigid bearing for the shaft 49, thus the thrust of the walls on the arms will be carried to the bracket, which will be overcome by the thrust from the opposite bracket. 5 The inner ends of the thimbles 55 are arranged with bearing plates 57 adapted to receive a roller 58 thereagainst, and the roller is mounted in eccentric position between a pair of disks 59 which are keyed or 10 otherwise fixed to the shaft 49 at opposite sides of the thimble 55.

The bracket 56 is preferably made in two parts which are bolted or otherwise suitably secured together, as shown at 60 in Fig. 8. 15 Turning of the thimble 55 forces the rod section or spindle 54 outwardly and thus lengthens the connecting rod between the presser bar and the operating shaft. The thimble 55 may be provided with a hexagon 20 surface midway of the opening 61 in bracket 56, thus making a suitable surface for applying a wrench for turning the thimble 55.

In Fig. 10 there is shown a slightly modified form of the presser bar carried at the 25 side of the machine. In this instance the presser bar is formed of a filler 63 of wood reinforced at opposite edges by angle irons 64 extending throughout the length of the presser bar and provided at its inner side 30 with attaching plates 65 suitably apertured for the reception of the outer ends of the threaded rod sections 54. The presser bar is thus reinforced and the desired resiliency and lightness in weight are obtained by use 35 of the wood filler 63.

The drive shaft 32 which is carried on the section 18 constitutes the main operating shaft of the machine and while, as above described, it may be caused to not only 40 effect the relative movements of the two sections 17 and 18, and also the expansion of the presser bars carried at the opposite sides of the section 18, it may also be operated for expanding the presser bars which are 45 carried upon the section 17. This latter operation is carried out by the following construction.

The section 17 is provided, preferably near 50 its upper end and along one side, with a shaft 66 having a feathered end 67 slidable through a sprocket wheel 68 which is retained between the said end of the section 18 and an angle bracket 69 on said end for holding the sprocket wheel 37 in line with 55 a chain 70 which passes over a sprocket wheel 71 freely mounted on the drive shaft 32. A second clutch element 72 is operable upon the shaft 32 for interlocking the sprocket wheel 71 thereto.

60 The clutch element 72 is operable by a lever 73 which projects from the adjacent end of the section 18 so that the operator may control the turning of the shaft 66 which is carried on the other section 17, irrespective 65 of the relative adjustment of the section 17

with respect to the section 18. The section 17 is provided with stub shafts 74 which extend in preferably a direction opposite to that in which the stub shafts 40 and 46 extend to permit the end pieces of the sections coming 70 into close proximity when they are collapsed or drawn together.

The stub shafts 74 are connected by worms 75 in the same manner above described in connection with the section 18 with the vertical shafts 49. The shafts 49 of the section 17 operate presser bars 76 carried at the opposite sides of the section 18 and connected to the ordinary shafts in the same manner as above described. The stub shafts 74 carry 80 sprocket wheels 77 over which pass chains 78 operated by sprocket wheels 79 mounted on the shaft 66 in line with the chains 78.

For the purpose of advancing the sections 85 relatively and vertically, one of the sections, such as the section 18, is provided on each end with a pair of transversely spaced apart standards 80 supporting a transverse shaft 81 at each end of the section 18, and the shaft 81 has on each end thereof a crank portion 90 82 to which is pivoted a connecting rod 83. The connecting rod 83 may be in one or more sections and extends downwardly in the adjacent upright 20 and is secured at its lower end to a bearing block 84 slideable vertically 95 in the adjacent upright 20. There is thus provided a pair of bearing blocks 84 at each end of the section 18. These bearing blocks are provided with rollers or other anti-friction devices for receiving horizontal rails 85 100 or the like, which project horizontally from the ends of the section 17 for holding the section 17 vertically rigid with respect to the slideable blocks 84, and for causing relatively vertical movement between the sections 17 105 and 18 when the blocks 84 are raised or lowered in their uprights 20.

The section 18 carries a platform 89 immediately beneath the mechanism surrounding the drive shaft 32, so that the operator 110 may be conveniently placed with respect to the clutches and other mechanism for controlling the movement and operation of the machine.

In the use of this machine, the same may 115 be placed in a trench and the expansion and contraction devices 51 manipulated so as to arrange the side rails 50 and 76 to clear the walls of the trench sufficiently for admitting the placing of piling against the walls. 120 The machine may be advanced or stepped downwardly by manipulating the shafts 81 which moves the slide bearings 84 and thus relatively and vertically advances the frames 17 and 18. When one frame is lowered, such as the frame 18, the side rails 50 125 thereof are expanded against the sides or piling to bind the piling against the walls of the trench and to support the machine from said rails. This is accomplished by turning 130

the operating shaft 32 after the clutch 35 has been shifted to operate the chain 38. The shafts 81 may now again be operated to draw the section or frame 17 downward, 5 and after the same reaches the desired lowered condition the side rails 76 of the frame 17 are expanded by operation of the shaft 32 through the clutch 72. The side rails 50 of the frame 18 are now contracted and the frame 18 is again advanced downwardly. 10 This operation is repeated until the machine reaches the desired depth in the trench.

The workmen in the trench are adapted to work in the machine, and the machine is 15 adapted to advance with the work so as to follow the workmen. To effect this result the operating shaft 32 is turned through the clutch 35 when shifted outwardly, to operate the chain 30 and thus advance one of the frames or sections, such as the section 17, 20 into an expanded position, as shown in Fig. 3. When in this position, the side rails 76 of the frame 17 are expanded to hold the section rigidly in the trench and support 25 the piling and walls of the trench. The rails 50 of the section 18 are now contracted and further operation of the advancing means through the chain 30 causes the section 18 to follow the section 17 and thus advance the remaining portion of the machine. 30

This step by step advancement of the machine causes it to feed or move forwardly, and the direction of movement of the machine is, of course, regulated by the binding 35 of the side rails 50 and 76 of the respective sections, so that while one section is anchored the other is drawn up to the anchored section.

The expanding and contracting of the 40 rails 50 and 76, as well as the horizontal advancement of the machine, is controlled from the single operating shaft 32 and its clutches 35 and 72. But one operator, therefore, need be employed, who may be located 45 on the platform 89 with the crank handle 32 and the clutch handles 36 and 73 within easy reach.

When sheet piling is used it is only necessary to use piling throughout the length of 50 the machine because as the machine is advanced horizontally the piling may be removed from the trench walls at the rear end of the machine and placed in front of the machine. The use of the machine eliminates the runners or horizontal braces and the trench or jack screws usually employed, and all of which consume considerable time and care in their application and shifting. 55

Sections 17 and 18 may be spread by re- 60 moving the three bolts that hold each half section together, then blocking same apart to the proper width of the trench, which allows the turn buckles or thimbles to take care of the unevenness of the trench.

65 When this machine follows a trench dig-

ging machine, which digs on a slant, the arms should be extended out in front of section 17, in order to place the sheet piling as soon as the earth is removed. That is so the machine can follow close to the digger and prevent any cave in. 70

It is obvious that those skilled in the art may vary the details of construction and arrangements of parts without departing from the spirit of my invention, and therefore I 75 do not wish to be limited to such features except as may be required by the claims.

I claim:

1. In a trench wall supporting machine, 80 the combination of a pair of relatively movable sections adapted to be placed in a trench, expanding means for the sections to individually bind the same in the trench, and means for effecting the relative movement of the sections to advance the same in 85 the trench upon the alternate anchoring of the sections in the trench by expansion.

2. In a trench wall supporting machine, 90 a pair of interfitting relatively slidable sections, means for relatively moving the sections, and means for independently expanding the sections for binding and anchoring engagement in the trench.

3. In a trench wall supporting machine, 95 the combination of a pair of interfitting relatively slidable sections, expanding rails carried upon opposite sides of each section, means for independently expanding the rails of each section whereby the sections may be alternately anchored in a trench, and means 100 for advancing one section when the other is anchored.

4. In a trench wall supporting machine, 105 the combination of a pair of slidable interfitting sections, means for moving said sections relatively in a vertical direction, means for moving said sections relatively in a horizontal direction, and means for independently anchoring the sections in a trench.

5. In a trench wall supporting machine, 110 the combination of a pair of relatively slidable sections, means for independently expanding the sections for alternately binding the same against the walls of the trench, and means for relatively moving the sections 115 to advance the machine in the trench.

6. In a trench wall supporting machine, the combination of a pair of relatively slid- 120 able sections, means for independently expanding the sections to bind against the walls of the trench, means for relatively moving the sections in a vertical direction, and other means for relatively moving the sections in a horizontal direction.

7. In a trench wall supporting machine, 125 the combination of a pair of relatively slid- able sections, means for individually bind- ing the sections against the walls of a trench to support said walls and to anchor the sections, means for vertically shifting one sec- 130

- tion relatively to the other when said other section is anchored, and means for shifting one of said sections horizontally when the other section is anchored.
8. In a trench wall supporting machine, the combination of a pair of relatively slideable sections, longitudinally disposed rails arranged at opposite sides of the machine and alternately secured to the sections, independent means for the sections connected to said rails for expanding the rails of each section for binding engagement against the walls of a trench to independently anchor the sections, and means for advancing a free section relatively to the anchored section.
9. In a trench wall supporting machine, the combination of a pair of relatively shiftable sections, means for advancing the sections relatively to each other, and means for individually expanding the sections for binding the same against the walls of the trench.
10. In a trench wall supporting machine, the combination of a pair of relatively movable sections, independent sets of side rails, one set for each section, independent means for expanding the sets of rails to individually anchor the sections against the side walls of the trench, and operating means on one section connected to the rail expansion means of both sections for selectively actuating the same.
11. In a trench wall supporting machine, the combination of a pair of interfitting relatively slideable sections, a set of expanding rails carried upon each section, expanding means carried on each section connected to the rails for binding the same against the walls of a trench to support the walls and individually anchor the sections in the trench, means for relatively sliding the sections to advance the machine in the trench, and a common operating means mounted on one of the sections and selectively connected to the advancing means and to the expanding means of the sections.
12. In a trench wall supporting machine, the combination of a pair of relatively slideable sections, independent sets of alternately arranged rails carried at opposite sides of the sections, and independent expansion means on each section for the rails thereof to bind the rails against the walls of the trench, operating means mounted on one section, means for selectively connecting the operating means to the expansion means of both sections for expanding the rails thereof, and advancing means between the sections and connected to said operating means for relatively sliding the sections when one section is free.
13. In a trench wall supporting machine, the combination of a pair of relatively slideable sections, advancing means connecting said sections together, independent sets of rails carried by the sections and arranged in alternate order at opposite sides of the machine, expansion means on each section connected to the rails thereof for binding the latter against the walls of the trench, and a common operating means on one section selectively connected to said advancing means and said expansion means of both sections.
14. In a trench wall supporting machine, a pair of relatively slideable sections, independent sets of rails, mounted on the sections, expanding means on the sections connected to the rails for independently binding the sets against the walls of the trench to support the walls and independently anchor the sections, operating means on one section, selective connections between the operating means and said expansion means of both sections, shifting means connecting the sections, a selective connection between the operating means and the shifting means, and means for vertically shifting the sections.
15. In a trench wall supporting machine, the combination of a pair of relatively slideable sections, shifting means arranged between the sections for relatively moving the same in a horizontal direction, a second shifting means arranged between the sections for shifting the same in a vertical direction, expansion means carried on each section for individually binding the same in the trench, and a common operating means on one section connected to both of said expanding means for selectively operating the same.
16. In a trench wall supporting machine, the combination of a pair of relatively shiftable sections, expansion means for each section for individually anchoring the section in the trench, a common operating means on one section, and a selective connection between the operating means and said expansion means adapted to operate but one of said expansion means at a time.
17. In a trench wall supporting machine, the combination of a pair of sections interfitting and adapted for relative vertical and horizontal movement, expanding means for each section to individually bind the sections in the trench, a vertically shifting means connecting the sections for raising and lowering the machine in the trench, and a horizontal shifting means connecting the sections operable independently of the vertically shifting means for advancing the sections horizontally in the trench.
18. In a trench wall supporting machine, the combination of a pair of sections each having a head on each end and arranged with the head of one section between the heads of the other section and the sections being adapted to slide one within the other, a crank shaft mounted on one section, a connecting rod between the cranks of said shaft and the other section, means for turning the

crank shaft to relatively shift said sections one within the other, expanding rails arranged at opposite sides of the sections, means on each section to expand the rails thereof, and an operating device for selectively operating the expanding means of each section.

19. In a trench wall supporting machine, the combination of a pair of sections each 10 having a head on each end and arranged with the head of one section between the heads of the other section and adapted for relative sliding movement in vertical and horizontal directions, vertically sliding bearing blocks on one section, horizontal projections on the other section adapted to move in said blocks, means on the first section connected to said blocks for moving the same vertically to shift the other section 15 vertically relative to the first section, shifting means carried by the first section and connected to the second section for moving the second section on the sliding block, and independent expansion means for the sections for independently anchoring the same 20 in a trench.

20. In a trench wall supporting machine, the combination of a pair of interfitting relatively slidable sections, sets of interfitting 25 rails arranged at opposite sides of the sections, independent expansion means carried by the sections and connected to the sets of rails for expanding first one set of rails to anchor its section in the trench and subse-

quently expand the other set of rails to 35 anchor the other set in the trench, and means for relatively moving the sections when one section is free.

21. In a trench wall supporting machine, the combination of a pair of interfitting sections, side rails carried by the sections, expansion means arranged upon the end of each section and connected to the opposite ends of the rails, a shaft on each section connecting together the expansion means at 45 the opposite ends thereof, a common operating mechanism on one section, and selective mechanism for connecting the operating mechanism to either one of said shafts for independently expanding the rails of the 50 sections.

22. The combination of a pair of interfitting frames, an operating shaft arranged vertically in each end of each frame, a shaft on each frame, connections between the opposite ends of the shafts and said first shafts of each frame, rails carried by each frame, horizontally expanding means between each of said first shafts and the opposite ends of the rails for moving the latter toward and 60 from the walls of a trench, selective operating means carried by one section and adapted for connection with both of said shafts for independently operating the same and selectively expanding the rails of the sections, and means for advancing a free section when the other section is anchored. 65

SYDNEY BURT GARDNER.
